PACK FOR USE IN REFRIGERATION ANESTHESIA

Filed Oct. 3, 1944

UNITED STATES PATENT OFFICE

2,438,643

PACK FOR USE IN REFRIGERATION
ANESTHESIA

Hazel E. Moore, Oakland, Calif.

Application October 3, 1944, Serial No. 557,012

2 Claims. (Cl. 62—1)

1

This invention relates to a method and means for producing refrigeration anesthesia on localized parts or areas of the human body or the like.

The use of refrigeration anesthesia is a comparatively new technique in the science of surgery and medical treatment. This technique provides a complete local anesthesia. Not only the nerves, but the whole living tissue substance is placed in frozen sleep with consequent freedom from pain and shock. Urgent operations may be postponed for longer periods and greater safety. Under the degree of cold that may be produced bacteria growth is materially checked, infection minimized, and the local metabolism is reduced to a point at which even a damaged blood supply may be sufficient to nourish the surviving tissue.

Refrigeration anesthesia is produced at the present time by placing crushed ice or iced packs directly in contact with the part or area of the human body upon which surgery is to be performed. It must remain there until the temperature of the localized area has been sufficiently cooled or reduced, and as the ice melts as it absorbs heat, water is continuously running off and wetting the mattress and bedding, particularly if the patient is bed-ridden.

The object of the present invention is generally to improve and simplify both the method and means whereby localized anesthesia by refrigeration is accomplished; to provide a method of cooling a localized area whereby the leakage or release of water is entirely eliminated; to provide a method whereby a cooling agent may be more efficiently applied to the area or part to be cooled; to provide a cooling or heat absorbing agent whereby temperatures below that of the melting point of ice may be maintained and a more rapid cooling effected; to provide a cooling or heat absorbing agent in the form of a pad, said pad containing an absorbent material adapted to be substantially saturated with brine or a like solution, said pad retaining its shape both in its frozen and melted state and liberating none of the brine when melted; and further, to provide a pad or pack consisting of a series of hingedly connected sections, each containing an absorbing material, said hingedly connected sections providing flexibility to permit the pad in its frozen state to be wrapped about or maintained in contact with the area to be cooled.

The method and means employed is shown by way of illustration in the accompanying drawings, in which:

2

Fig. 1 is a perspective view of a human leg showing the application of one of the packs.

Fig. 2 is a perspective view of a pack partly broken away.

Fig. 3 is an enlarged longitudinal cross section of a portion of the pack shown in Fig. 2.

Fig. 4 is a plan view showing a modified form of pack particularly intended for application to flat or seemingly flat surfaces such as the back or chest, etc.

Fig. 5 is a plan view of a shoulder pack; and,

Fig. 6 is a vertical cross section of a two compartment pack.

Referring to the drawings in detail, and particularly Figs. 2 and 3, A indicates in general a pack which consists of two sections of a suitable cloth or fabric such as indicated at 2 and 3. These fabric sections are sewn or stitched transversely to form a series of compartments 4 which are filled with saw-dust or any other suitable liquid absorbing material such as indicated at 5. There are two spaced apart sewn seams 6 and 7 between two compartments and these seams, together with the fabric between the seams form a flexible or hinge-like connection between these compartments. These hinge-like connections are important and will be hereinafter more fully described.

In Fig. 2 the seams 6 and 7 are disposed on an angle or bias to the sides 9 and 10 of the pack, and it is of course understood that there are seams 11 running parallel to the sides so as to close the ends of the respective compartments. Also it will be noted that two spaced apart seams 14 and 14 extend centrally and longitudinally of the pack, thus forming a longitudinally extending flexible or hinge-like connection intermediate the compartments and in addition to the flexible connections formed between them.

In Fig. 4 a plurality of spaced seams extend longitudinally of the pack as indicated at 16 and a plurality of spaced seams 17 are also provided which extend transversely of the pack, thus forming a series of compartments which are hingedly connected at their sides and ends and at right angles to each other while in Fig. 2, the transverse seams are on a bias. Also in Fig. 2 tapes 18 are provided at each end whereby the pack may be tied in place, while in Fig. 4 eyelets are placed at each end to receive one or more tapes which may be employed to lace or tie the pack in place when in use.

The type of pack shown in Fig. 2 is particularly intended for use as a spirally wound pack, for instance when applying it to the arm or leg or

knee as shown in Fig. 1, while the pack shown in Fig. 4 is more suitable for applications, for instance to the back, chest or abdomen.

The pack shown in Fig. 5 is intended for a shoulder pack and may be tied in place as shown at 19 or the like. In this pack the spaces 4a indicate the compartments containing the absorbent and the spaces 6a the flexible or hinge-like connections between them. In Fig. 6 a two-compartment pack is shown. One compartment, for instance the one indicated at 20, may be employed to receive an ice bag 21, while the compartment 22 may contain a pack 23 containing a liquid absorbent. The fabric forming the two-compartment pack may be rubberized if desired.

The several types of packs shown are by way of illustration only, as many other forms may and have been designed. The important feature to bear in mind is that hinge-like or flexible connections must be provided between the compartments containing the absorbent as the packs are often subjected when placed in a refrigerator to a sufficiently low temperature to freeze them solid. In that case an ordinary pack would be stiff as a board and would be difficult to apply except on comparatively flat surfaces, but by permitting the fabric itself to form a hinge-like connection between each compartment even though the absorbent material is frozen stiff, the fabric between the compartments will permit sufficient flexibility so that the pack will conform to the surface applied. For instance, in Fig. 1 the type of pad shown in Fig. 2 may be wrapped around the leg and knee and even though it is frozen stiff as the fabric formed between the compartments will remain flexible.

In actual practice the sawdust, if that type absorbent is used, may be saturated with water, or it may be saturated with a brine solution of any strength desired. If water is used, it will obviously become frozen at a temperature of 32° F. This is sufficiently cold for many uses. Where a greater degree of cold is desired, the brine solution will be employed. For instance, a weak solution may freeze at 30° F., a stronger solution at 28° F. and so on, the temperature required for the pack determining the strength of the solution.

The bias arrangement of the compartments shown in the pack of Fig. 2 is very desirable where spiral wrapping is required as shown in Fig. 1. This arrangement is not required for other uses. For instance, application to the shoulder of a person is taken care of by the type of pack shown in Fig. 5, and abdominal pack, as shown in Fig. 4. An ordinary ice pack in combination with an absorbent pack may be applied when a double container is used, as shown in Fig. 6, and substantially any degree of cold may be obtained by varying the strength of the brine solution.

It has heretofore been stated that the absorbent material placed in the compartments, whether it be sawdust or otherwise, is substantially saturated with a liquid, for instance water or brine or otherwise. It should, however, be understood that the degree of saturation is less than complete saturation so that there will be no tendency for water or brine to run off or drip when the pad has absorbed its maximum quantity of heat. By maintaining the saturation less than full saturation, it is obvious that the wetting of mattresses, bedding and so on is entirely avoided and that due to the flexibility of the pads better contact with the part or area to be cooled is in-

sured and quicker cooling effected. As the pads are constructed of ordinary cloth or fabric, and sawdust or like absorbent is used in conjunction therewith, it is obvious that they may be boiled or sterilized as often as necessary. The packs have many uses, for instance:

1. To obtain anesthesia for amputation of limbs and many minor surgical procedures;
2. To cool limbs or areas of the body inflicted with overwhelming infection;
3. To diminish pain following trauma;
4. To diminish pain in extremities following operations;
5. To treat certain cases of concussion and fevers.

The above enumerated uses are merely a few of the numerous applications to which the pad may be put. Any suitable type of refrigerator may be employed to cool the packs to any degree desired, but obviously a refrigerator of sufficient capacity should be employed to permit a considerable number to be contained therein at the same time so that a sufficient supply will be at hand for each case as it may be. Thus, after a pad has been applied and has reached the melting point or close thereto, another pack may be taken from the refrigerator and applied and so on until the limb or part to be cooled has reached the temperature to be desired. While these and other features of my invention have been more or less specifically described and illustrated, I nevertheless wish it understood that the materials and finish of the several parts employed may be changed to suit varying conditions and that other changes may be resorted to within the scope of the appended claims.

Having thus described my invention, what I claim and desire to secure by Letters Patent is:

1. A pack for use in refrigeration anesthesia comprising an absorbent material in the form of sawdust, a fabric material confining the absorbent, said fabric having sewed seams forming a plurality of compartments each containing the absorbent and the fabric between the compartments forming flexible connections between them, and a brine solution substantially saturating the fabric and the absorbent.

2. A pack for use in refrigeration anesthesia comprising an absorbent material in the form of sawdust, two sheets of pervious fabric material covering and confining the absorbent, said sheets forming long strips sewed along their sides and ends to confine the absorbent, pairs of closely spaced seams sewed on the bias crosswise of the strips and dividing the strips into transverse compartments with hinges between the pockets, a pair of closely spaced seams sewed longitudinally on the strips and centrally with relation to the sides of the strips, said seams dividing the pockets transversely and forming hinges between the pockets, said absorbent material and fabric adapted to be saturated with a brine solution and securing means at each end of the strips.
